UNITED STATES PATENT OFFICE.

CHARLES A. BATES, OF MARSHALLTOWN, IOWA.

BELL-RINGER.

1,114,671.

Specification of Letters Patent.

Patented Oct. 20, 1914.

Application filed August 27, 1913. Serial No. 786,919.

To all whom it may concern:

Be it known that I, CHARLES A. BATES, a citizen of the United States, residing at Marshalltown, in the county of Marshall and 5 State of Iowa, have invented new and useful Improvements in Bell-Ringers, of which the following is a specification.

This invention is an improved locomotive bell ringer adapted to be operated by compressed air or other fluid under pressure, for automatically swinging a locomotive bell and causing the same to ring, the invention consisting in the construction, combination and arrangement of devices hereinafter 15 described and claimed.

The object of my invention is to provide an improved form of engine, adapted to be operated by compressed air, steam or other fluid under pressure and which engine 20 is cheap and simple in construction, is adapted to be readily attached to one side of the stand or frame on which a bell is mounted and to be connected to the crank arm of the bell for swinging the latter.

25 In the accompanying drawings:—Figure 1 is an elevation of a locomotive bell ringer constructed in accordance with my invention, showing the same attached to a locomotive bell in operative relation thereto. 30 Fig. 2 is an elevation of the same at right angles to Fig. 1. Fig. 3 is a vertical central sectional view of the engine, the piston, the piston rod and the valve being shown in elevation. Fig. 4 is a transverse sectional view on the plane indicated by the line 35 *a—a* of Fig. 3.

In accordance with my invention, I provide a cylinder 1 which is here shown as formed with an integral bottom or lower 40 head 2 and a detachable upper head 3, the latter being secured by bolts 4 to a flange 5 with which the cylinder is provided. On opposite sides of the cylinder at a suitable 45 distance from its upper end are supporting arms or lugs 6 which are adapted to be bolted or otherwise suitably secured to one side of the frame 7 in which a locomotive bell 8 is mounted. In the bottom of the cylinder is a drain opening 9 provided with 50 a plug 10. At one side of the cylinder is a connection 11 to which the air supply pipe from the air brake apparatus of the locomotive on which the bell and its ringer are used may be attached, to enable the 55 compressed air from the air brake apparatus to be used as the motor fluid for operating the

engine. An inlet port 12 is formed in the same side of the cylinder and communicates with the connection 11, this inlet port being intermediate the ends of the cylinder and 60 somewhat above the center thereof. In the opposite side of the cylinder there is a passage 13 which is vertical and which communicates with the cylinder through an inlet port 14 which is at a slightly lower plane 65 than the port 12, a second port 15 which is spaced a slight distance below the port 14 and the said passage also communicates with the lower end of the cylinder through a port 16.

An exhaust port 17 is here indicated in the same side of the cylinder with the passage 13 and located near the upper end of the cylinder. A piston 18 is fitted in the bore of the cylinder for vertical movement 70 therein and is provided with spring packing rings 19. The piston rod 20 which extends upwardly from the piston passes through an opening in the center of the upper head 3 and is provided at its upper end with a 75 reduced extension 21, the upper side of which is formed with a substantially semi-circular recess 22. This extension is also provided with a transverse opening 23. The piston rod is provided near its lower 80 end with a pair of transverse adjusting openings 24—25, the latter slightly above the former and is also provided at a suitable distance from its upper end with an 85 opening 26.

A tappet pin 27 which is here indicated as a spring cotter may be placed either in the opening 24 or the opening 25 and a similar tappet pin 28 is placed in the opening 26. I also provide a valve 29 which is tubular 90 in form and is provided near its upper and also its lower ends with packing rings 30 so that an annular circumferential channel 31 is formed medially around the said valve. This valve is fitted for vertical reciprocating 95 movement in the bore of the cylinder, above the piston, between the tappet pins 27—28 and the piston rod extends through and is vertically movable in the said valve. The length of the space between the tappet pins 100 exceeds the length of the valve so that as the piston moves upwardly or downwardly, one of its tappet pins as it nears the end of its stroke engages the valve and, hence, moves the latter with the piston, the initial movements of the piston being independent of 105 the valve as will be understood.

110

The crank arm 32 of the bell has its wrist 32^a engaged in an elongated slot 33^a of an arm 33^b which forms an upper extension of a pitman 33^c, the pitman being 5 screwed to the lower end of the said arm and having a lock nut 33^d. At the lower end of the pitman is a ball 34 which fits in the recess 22 of the piston rod and the upper side of which is engaged by a sleeve 10 35 which coacts with the recess 22 to form a socket for the reception of the ball 34. The lower end of said sleeve fits on the reduced portion of the piston rod and is secured thereto by a bolt 36 which passes through 15 the opening 23 and also through openings in opposite sides of the sleeve. The slotted arm 33^b permits the bell crank to make a complete circle when the bell is swung hard enough to pass over the upper dead center. 20 It will be understood that when the engine is in operation, the vertical reciprocating movement of its piston causes the bell to be swung first in one direction and then in the other and, hence, the bell is struck by 25 its clapper at each end of each stroke.

The operation of the engine is as follows:—Compressed air enters at the port 12 and passes around the valve to the port 14 on the opposite side and then down through 30 the passage 13 and the port 16 to the lower end of the cylinder and under the piston, driving the piston up until the lower pin 27 strikes the lower end of the valve 29 and moves the valve upwardly, thereby causing 35 the valve to close the port 14 and open the second port 15, thus cutting off further supply of compressed air to the cylinder and allowing the air to exhaust from under the piston through the valve to the top of the 40 cylinder and out through the exhaust port 17 to the atmosphere. This upward movement of the piston throws the bell up; the weight of the bell then moves the piston downwardly and just before it gets to the 45 bottom of the cylinder, the tappet pin 28 strikes the upper end of the valve, moving

the latter downwardly and thus causing the valve to close the port 15 and reopen the inlet port 14. Port 17 is open to the atmosphere at all times and any leakage by any 50 of the packing links is free to escape. The port 12 is never closed by the valve. It will be observed that the valve is balanced and, hence, it moves very easily in either direction. 55

To vary the length of the stroke of the piston, the lower tappet pin will be placed in an appropriate adjusting opening, 24 or 25 of the piston rod, as the case may be.

I claim:—

In apparatus of the class described, a cylinder having a medially located intake port on one side, an exhaust port near the upper end and a passage in one wall communicating with the lower end of the cylinder and having an inlet port near the center of the cylinder and a second port below and spaced from the inlet port, in combination with a piston in the cylinder having a rod extending through the upper head thereof, a tubular valve fitted and movable in the bore of the cylinder and also movable toward and from the piston rod, said valve having a bore extending therethrough from end to end of greater diameter than the piston rod 75 and also having a pair of spaced heads forming an annular chamber around the said valve and with which the intake port of the cylinder communicates, and tappets on the piston rod to successively engage and move the valve as the piston nears the limit of its stroke, one of said tappets serving on the up stroke of the piston to cause the lower head of the valve to close the inlet port and open the second port. 80

In testimony whereof I affix my signature in presence of two witnesses.

CHARLES A. BATES.
